UNITED STATES PATENT OFFICE.

JEREMIAH CAMPBELL, OF PROVIDENCE, RHODE ISLAND.

HOISTING APPARATUS.

No. 816,071.

Specification of Letters Patent.

Patented March 27, 1906.

Application filed January 14, 1905. Serial No. 241,086.

To all whom it may concern:

Be it known that I, JEREMIAH CAMPBELL, a citizen of the United States, residing at Providence, in the county of Providence and State of Rhode Island, have invented a new and useful Improvement in Hoisting Apparatus, of which the following is a full, clear, and exact description, reference being had to the accompanying drawings, forming a part 5 of this specification, in explaining its nature.

My invention belongs to that general type of ore or coal hoisting and handling machinery in which the bucket is passed directly and vertically through the hopper before and after relieving its load into the same and in 15 which the hopper comprises movable sections or segments actuated upon movement of the bucket to provide for the passage of the latter.

More particularly, my invention relates to 20 a hopper of the type referred to in which the movable sections have a novel construction and mode of action and operate in connection with the bucket mechanism to open and close a passage for the bucket through the 25 hopper.

An object of my invention is the provision 30 of positive and reliable connections between the hopper-sections and the bucket mechanism whereby the hopper may be opened as well as closed by said mechanism instead of opening by gravity, as heretofore.

Another object of my invention is a breaking 35 and crushing device which serves the double purpose of separating to a certain extent the larger from the smaller pieces of coal during their exit from the hopper and also should the coal jam in the mouth of the hopper of breaking the larger pieces and driving the obstructing mass through the outlet. It 40 has been found that such choking frequently results from the feeding through a narrow passage of large and small coal mixed together the small coal acting to lock the larger, and the portion of my invention last above referred to serves the double purpose of preventing this locking by separating the sizes to a certain extent and should any of the pieces be too large or should such locking 45 still occur by breaking the larger pieces and driving the mass through the opening. It will be remembered that the hopper-outlet is smaller in area than the average cross-area of the hopper itself.

More specifically, my invention relates to 50 a hopper, one section of which when in its closed position acts as a device to select or

divide and guide the coal to the chute and operates when opening to permit of the exit of the bucket to act as a device for crushing and sizing the larger coal as it passes into the 60 chute.

Other objects of my invention will presently appear upon a description of the same, in connection with the accompanying drawings, in which—

Figure 1 is a cross-sectional elevation of my assembled apparatus in one position. Fig. 2 is a cross-sectional elevation on the line 2 2 of Fig. 1. Fig. 3 is an elevation of the cross-head and guiding mechanism. Fig. 4 is a 70 plan on the line 4 4 of Fig. 3. Fig. 5 is a plan on the line 5 5 of Fig. 1. Fig. 6 is a cross-sectional elevation of the cross-head guide-plate in engagement with the bucket-suspender. Fig. 7 is a top plan of the mechanism shown 75 in Fig. 6. Fig. 8 is a side elevation of a modification, Fig. 9 being a vertical section on line 9 9 of Fig. 8, showing one side of the hopper. Fig. 10 is an enlarged section taken on line 10 80 of Fig. 9.

Referring to the various figures, the hopper 1 is shown having the throat or extension 2 for feeding the chutes at 3. The bottom of the hopper has the usual slope to the throat and is comprised of two plates or sections 4 85 and 5, the section 4 being hinged at 6 to have a downward swing from the position shown in Fig. 1 and the section 5 hinged at 7 to swing upward from the position shown in this figure.

The bucket or grab 9 is shown in Figs. 1 90 and 2 connected with the hoisting-chain 10 by the link 11, (see Fig. 6,) the link being attached to the chain at the eye 12 and to the grab by the eye-link 13. The link 11 is provided with the usual buffer-spring 14 and is 95 provided with a plate 15 and lug 16 for engaging with the cross-head presently to be described.

Upon the sides of the hopper are provided 100 the guideways 17, (see Figs. 3 and 4,) and in these guideways are adapted to slide the guide-bars 18. Carried by the guide-bars is the cross-head 19, suitably braced and connected thereto. The cross-head is provided with a central opening 20 for the passage of the link 11 and hoisting-chain and has mounted thereon a guide-plate 21, having also an opening registering with the opening in the cross-head for the passage of the bucket or grab connection. Upon the sides 110 of the hopper are provided a second set of ways 22, cammed or deflected inward at 23

as shown in Figs. 3 and 4 and as indicated in the dotted lines in Fig. 2. Engaging these camways by means of fingers 23' and extending through guides 24 on the cross-head 19 are the links 25, adapted to have a reciprocating movement in said guides by virtue of their engagement with the camway. The links 25 extend to the center of the cross-head, passing through the openings 26 in the guide-plates 21 and terminating in the collars 27. (See Figs. 6 and 7.) These collars have a short diameter at least equal to that of the central opening in the cross-head and are of an elongated shape. When the fingers 23' of the links 25 coacting with the cams 23 are in their outermost position, the collars 27 are in the position shown in Fig. 7, overlapping each other at the center of the cross-head sufficiently to permit of the engagement of each 15 with the link 11 and yet intersecting or crossing the passage of the central opening 20 and interposed in the line of action of the piece 16 on the link 11. When, however, the links 25 by virtue of their engagement with the camways are carried to their inward position, the ends of the collars 27 do not lie in the line of the opening 20.

Secured to or integral with the cross-head guide-bars 18 are the racks 28, and pivotally connected to the bars 18 are the links 29. The plates 30 serve to house the moving parts to prevent interference of the coal therewith. The links 29 are pivotally connected to the lugs 31 on the plate 4. The racks 28 engage the pinions 32, mounted on the housing 30, (see Figs. 1, 2, and 5,) and are held in working engagement therewith by the rollers 32'. The pinions 32 are shown as of considerable width and besides engaging with the racks 28 engage also with the segmental rack 33 on the frame of the plate 5.

The ore selecting, dividing, and crushing feature of my invention is as follows: Upon the upper face of the plate 5 is a series of ribs 34. These ribs are shown as tapering upward from the surface of the plate toward the mouth of the hopper and terminate in a point at a cutting or crushing edge 35. The throat 2 of the hopper is curved at 36, as shown in Fig. 1, the curve being described by a radius the center of which would be in the neighborhood of the point of the ribs 34. The curve 36 terminates at the mouth of the hopper, and located in the mouth at an angle to 50 be substantially a continuation of the curve of the wall is a grate 37. This is composed of a series of bars 38, (see Fig. 5,) arranged parallel to the plane of the ribs 34. The upper edges of the bars are pointed at 39, and the 55 radius of action of the crushing-point 35 is such as to cause the ribs to coact in crushing with that portion of the grate-bars lying to the outside of the points 39.

The operation of my apparatus is as follows: The bucket being below the hopper

and the hopper open, upon upward movement of the chain 10 the plate 15 on the link 11, connected therewith, engages the under side of the cross-head, as shown in Fig. 6, and carries the cross-head, with its guides, upward 70 in the guideway 17. The links 29, pivotally connected to the guides and to the plate 4, in moving upward draw the plate 4 into the position shown in Fig. 1, while the rack 28, moving upward, by engagement with the pinion 32 rotates the pinion, and the pinion engaging the rack 33 turns the plate 5 downward into the position shown in Fig. 1. The bucket is then relieved by suitable means, and the coal falling upon the plates 4 and 5 80 slides downward toward the chute. The larger coal passes down along the tops of the ribs 34 and over the end thereof, lodging on the grate 37, being retained on the outside portion of the grate by the points or projections 39 on the upper edge of the grate-bars. The smaller coal passing down between the ribs drops off the end of the plate 5 and passes down between the bars of the grate inside of the projecting points 39, such points 90 serving to prevent the larger from obstructing the passage of the smaller coal. The bucket having been relieved is allowed to start downward upon its return trip. The cross-head is at this time in its uppermost position, as shown in Fig. 2, and the fingers 23' of the links 25 in the outermost line of the camways 22. On moving down the link 11 by means of the lug 16 engages the links 25 at their collars, as shown in Figs. 6 and 7, and starts downward with the cross-head, to which it is for the time positively connected, the guides 18 moving in the guideways 17 and the links 25 engaging the camways 22. During this time the link 29, engaging the 105 plate 4, throws it downward into a substantially vertical position, and the rack 28, engaging the pinion 32 and the pinion on the segmental rack 33, causes the plate 5 to swing upward on its pivot 7. The rotary movement of the plate 5 causes the points 35 of the knives or crushers 34 to crush the larger coal then resting upon the outer section of the grate, and this crushing action is rendered effective, as it is primarily caused by the great 110 weight of the empty grab, which being connected to the cross-head at this time serves as the motive power by which this crushing action is caused to take place. On arriving opposite the inward bend 23 in the camways 120 the links 25 are forced inward and their collars are moved beyond the central opening 20 in the cross-head and out of the way of the lug 16, so that the lug 16, with the chain, passes on through the opening 20 and leaves the 125 cross-head there located.

The movement upward of the plate 5, which forms the lower part of the bottom of the hopper when the hopper is closed, is of great advantage, because as more coal runs over this 130

portion of the hopper than over the upper plate 4 there is more likelihood that some of the fine dust will stick to it—for example, if the plate is wet. If, however, this plate is moved into a practically vertical position, as it is in the operation above described, the finer coal will not tend to stick to it, and for this reason the hopper is more nearly self-cleaning than such hoppers are usually.

10 It is apparent that other means may be adopted for moving the two plates which form the floor of the hopper; but I believe the above to be efficient and especially desirable because of the positive connection by which the weight of the grab in its descent not only requires the operation of the plates, but also serves as the means of power for operating the crusher.

I have shown in Figs. 8, 9, and 10 a modification of the mechanism for operating the plate 5 which in some cases is preferable to that shown in the other figures. Briefly, it consists in the operation of the pinion 32 by means of chains and sprockets instead of by racks. For this purpose each pinion 32 is fast on a stud extending through the housing and carrying at its outer end a sprocket 40. Similar sprockets 41 are suitably mounted in the upper part of the hopper in the same plane with the sprockets 40, so that there is a pair of sprockets on each side of the hopper. A chain 42 passes around each pair of sprockets, the ends of each chain being fastened to a pin 43, which is connected to and moves with the cross-head, so that as the cross-head is lowered the chains cause the lifting of the plate 5 in a manner similar to the action of racks 28. The lifting of the cross-head lowers the plate 5. Fig. 8 shows the parts in their 35 position when the bucket or grab is lowered, and Fig. 10 shows one of the pins 43 and its connection with the cross-head 19. In this view, which is a section on line 10 10 of Fig. 9, the cross-head has an extension on each side which extends out between the guideways 17. This extension comprises a plate 44, which is clamped between two angle-pieces 45 45, connected by the plate 46, and serves to give clearance for the chain. The 45 pin 43 is attached to the structure so formed, this forming a convenient and strong mode of attachment therefor.

It is apparent that the precise construction shown and described is capable of varied 55 modifications without involving a departure from the spirit of my invention.

What I claim as my invention is—

1. In a coal-delivering mechanism, a movable grab, a stationary hopper having a plate 60 movable to provide a passage for the grab into the same, means engaging said plate and positively actuated by the grab to open said passage.

2. In a coal-delivering mechanism, a vertically-movable grab, a stationary hopper

having a bottom plate movable to provide a passage for the grab into the same, means engaging said plate and positively actuated by the grab to open said passage.

3. In a coal-delivering mechanism, a movable grab, a stationary hopper having a plate 70 movable to provide a passage for the grab into the same, operating means engaging said plate, and means actuated by the grab to positively engage said operating means to 75 open said passage.

4. In a coal-delivering mechanism, a vertically-movable grab, a stationary hopper, the bottom of which comprises a plate pivotally mounted to open and close with the exit and entrance of the grab, and means for opening said plate upward and into the hopper.

5. In a coal-delivering mechanism, a vertically-movable grab, a hopper, the bottom 85 of which comprises two plates pivotally mounted to open and close with the exit and entrance of the grab, and means for opening one of said plates upward and into the hopper, and the other downward and away from 90 the hopper.

6. In a coal-delivering mechanism, a vertically-movable grab, a hopper, the bottom of which comprises a plate pivotally mounted to open and close with the exit and entrance of the grab, and a chain and sprocket 95 actuated by the grab to operate said plate.

7. In a coal-delivering mechanism, a vertically-movable grab, a hopper, the bottom of which comprises two plates pivotally 100 mounted to open and close with the exit and entrance of the grab, a chain and sprocket for operating one of said plates, and a pivoted link for operating the other plate.

8. In a coal-delivering mechanism, a vertically-movable grab, a stationary hopper, the bottom of which comprises a plate pivotally mounted to open and close with the exit and entrance of the grab, means engaged by the grab on its downward movement to open 110 said plates.

9. In a coal-delivering mechanism, a vertically-movable grab, a hopper, the bottom of which comprises a plate pivotally mounted to open and close with the exit and entrance of the grab, means engaged by the grab on its downward movement to open 115 said plate, and means for releasing the grab from said plate-opening means after a predetermined travel.

10. In a coal-delivering mechanism, a vertically-movable grab, a hopper, the bottom of which comprises a plate pivotally mounted to open and close with the exit and entrance of the grab, a cross-head engaged by 125 the grab on its downward movement to open said plate.

11. In a coal-delivering mechanism, a vertically-movable grab, a hopper, the bottom of which comprises a plate pivotally mount- 130

- ed to open and close with the exit and entrance of the grab, a cross-head engaged by the grab on its downward movement to open said plate, and a latch to engage and release the cross-head from the grab after a predetermined travel.
12. In a coal-delivering mechanism, a vertically-movable grab, a hopper, the bottom of which comprises a plate pivotally mounted to open and close with the exit and entrance of the grab, a cross-head engaged by the grab on its downward movement to open said plate, and a latch comprising a link mounted on the cross-head and slidable thereon.
13. In a coal-delivering mechanism, a vertically-movable grab, a hopper, the bottom of which comprises a plate pivotally mounted to open and close with the exit and entrance of the grab, a cross-head through an opening in which the grab connection passes, means secured to the cross-head and slidable thereon to engage and release the grab connection, a cam on the hopper to actuate said slideable means, and means actuated by the cross-head to operate the pivoted plate.
14. In a coal-delivering mechanism, a vertically-movable grab, a hopper, the bottom of which comprises a plate pivotally mounted to open and close with the exit and entrance of the grab, a cross-head through an opening in which the grab connection passes, means secured to the cross-head and slidable thereon to engage and release the grab connection, a cam on the hopper to actuate said slideable means, a sprocket operated by the cross-head and gearing operated by the sprocket to operate the pivoted plate.
15. In a coal-delivering mechanism, a vertically-movable grab, a hopper, the bottom of which comprises two plates pivotally mounted to open and close with the exit and entrance of the grab, a cross-head through an opening in which the grab connection passes, means secured to the cross-head and slidable thereon to engage and release the grab on its downward movement, a cam on the hopper to actuate said slideable means, other means for engaging the grab connection upon its upward movement, means connected with the cross-head and plates for operating the plates upon movement of the cross-head.
16. In a hopper having an opening contracted to prevent the free passage of large ore, means to prevent the large ore, held at said opening, from interfering with the passage therethrough of small ore.
17. In a hopper having a contracted opening, means for separating the small from the large ore, and for causing the small ore to freely pass through said opening without being obstructed by the large ore.
18. In a hopper having a contracted opening, means for separating the small ore from the large ore and for holding the large ore out of the path of the small ore through the opening.
19. In a hopper having an opening, a grate in said opening, a series of ribs at the throat of the opening between the ends of which the small ore may pass to the grate, means for preventing the obstruction of the grate by the large ore.
20. In a hopper having an opening, a grate in said opening, the surface of which is divided into two sections by a line of prongs or projections on the bars of the grate, a series of ribs at the throat of the hopper between the ends of which the small ore may pass to the inside section of the grate-surface, while the large ore passes over the ends of the ribs and lodges upon the outside section.
21. In a hopper having a restricted outlet, a pivoted crushing or sizing device operative in the direction through said outlet to keep said outlet clear and means whereby said crushing device is oscillated toward and from the outlet.
22. In a hopper having a restricted outlet, a grate in said outlet, and a pivoted crushing or sizing device coacting with the grate to keep the outlet clear.
23. In a hopper having a restricted outlet, a pivoted plate having a series of pointed ribs to crush and size the ore at the outlet.
24. In a hopper having a restricted outlet, a bottom plate of said hopper being pivoted to swing in the direction of the said outlet and provided with means to crush or size the ore to keep the opening clear.
25. In a hopper having a restricted outlet, a bottom plate of said hopper being pivoted to permit the passage of a grab, and provided with a series of pointed ribs to crush or size the ore at the outlet.
26. In a hopper having a restricted outlet, a bottom plate of said hopper being pivoted to permit the passage of a grab, and provided with a series of ribs sufficiently spaced to catch and guide the smaller ore and provided with knife or crushing ends to crush or size the larger material at the outlet when opening to admit the grab.
27. In a hopper having a restricted outlet, a grate across said outlet, the base of the grate being formed to divide the grate-surface into two sections, a bottom plate of said hopper pivoted to permit the passage of a grab and provided with ribs sufficiently spaced and arranged to catch and guide the smaller ore to the inside section of the grate-surface, and extended to points acting upon movement of the plate to crush the larger ore against the outside section of the grate-surface.
28. In a hopper having a restricted outlet, and a bottom plate movable to permit the passage of a grab, means acting by the movement of said plate to crush or size the ore at the outlet.

29. In combination a hopper having a restricted outlet, a grab and means operated by the grab to crush or size the ore at the outlet.
- 5 30. In combination a hopper having a restricted outlet and a grab, a bottom plate of said hopper positively actuated by the grab to crush or size the ore at the outlet.
31. In combination a hopper having a re-
- stricted outlet and a grab, a bottom plate of said hopper actuated by the grab to be swung upward into the hopper and crush or size the material therein.

JEREMIAH CAMPBELL.

In presence of—

F. F. RAYMOND, 2d,

M. E. FLAHERTY.
